DESIGN FOR AN ELECTRICAL TRANSFORMER

Walter J. Garlick, Jr., Glen Ridge, N. J., assignor
to American Transformer Company, Newark,
N. J.

Application August 13, 1938, Serial No. 79,322

Term of patent 7 years

To all whom it may concern:

Be it known that I, Walter J. Garlick, Jr., a citizen of the United States, residing at Glen Ridge, in the county of Essex and State of New Jersey, have invented a new, original, and ornamental Design for an Electrical Transformer, of which the following is a specification, reference being had to the accompanying drawing, forming a part thereof.

Figure 1 is a view looking down on the top of the transformer.

Figure 2 is a view looking upwardly at the bot-

tom of the transformer showing the plates covering the compound filling openings into the end bracket chambers.

Figure 3 is a side elevation of the transformer, looking at Figure 1 from right to left.

Figure 4 is an end elevation of the name plate end of the transformer.

I claim:

The ornamental design for an electrical transformer, as shown.
